Primary Examiner — Robin V Webster(74) *Attorney, Agent, or Firm* — Pedersen and Company, PLLC; Ken J. Pedersen; Barbara S. Pedersen**CLAIM**

The ornamental design for a filter block for liquid filtration, as shown and described.

DESCRIPTION

FIG. 1 is a front-right perspective view of the invented design for a filter block for liquid filtration.

FIG. 2 is a front view of the filter block of FIG. 1, wherein the right side view would be a mirror image of the front view.

FIG. 3 is a rear view of the filter block of FIG. 1, wherein the left side view would be a mirror image of the rear view.

FIG. 4 is a top view of the filter block of FIG. 1.

FIG. 5 is a bottom view of the filter block of FIG. 1; and, FIG. 6 is a cross-sectional view of the filter block of FIG. 1, viewed along line 6-6 in FIG. 4, and wherein stippling indicates the cut surface.
